DEVICE FOR SUPPORTING AND ACTUATING HYPODERMIC SYRINGES

Filed Oct. 10, 1951

Fig. 1.

UNITED STATES PATENT OFFICE

2,660,169

DEVICE FOR SUPPORTING AND ACTUATING
HYPODERMIC SYRINGES

Henry Malm, New York, N. Y.

Application October 10, 1951, Serial No. 250,615

7 Claims. (Cl. 128—218)

1

This invention relates to devices for supporting and operating hypodermic syringes and the like in the operation of injecting a fluid into the body. More particularly, the invention deals with a device including means for gripping or pinching the flesh for positioning the device on the body, preparatory to quickly injecting the needle of the syringe into the pinched area. Still more particularly, the invention deals with a device of the character described, wherein the syringe is supported in raised position under tension and is quickly released by means of a trigger facilitating a fast movement of the needle into the body.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a side view of a device made according to my invention, diagrammatically illustrating the method of its use and indicating the syringe of the device in operative position in dot-dash lines.

Fig. 2 is a view looking in the direction of the arrow 2 of Fig. 1 on an enlarged scale and with part of the construction broken away and in section.

Fig. 3 is a partial section on the line 3—3 of Fig. 2.

Fig. 4 is a sectional plan view on the line 4—4 of Fig. 1; and

Fig. 5 is a fragmentary view of part of the device in Fig. 1 showing a modification.

In Fig. 1 of the drawing, I have shown one of my improved syringe supporting and operating devices 10, in which a conventional syringe 11 is detachably mounted. The syringe comprises a lower tube 12, having a detachable nozzle 13, at its lower end, which supports the needle 14. The tube 12 has, at its upper open end, an enlarged flange 15 which is flattened on opposed sides, as seen at 16, note Fig. 4. Supported in the tube 12 is the conventional plunger 17 controlling discharge of medication through the needle 14.

The device 10 comprises an elongated tubular body or casing having a large diameter upper end 18, the large diameter lower collar 19 and an intermediate smaller diameter portion 20. Extending through this tubular body is a bore which freely and snugly receives the tube 12, as will clearly appear from a consideration of Fig. 3 of the drawing.

2

The upper enlarged diameter portion 18 of the tubular body has, at opposed sides thereof, an upper extension 22 and a lower extension 23 and in these parts are formed vertical passages 24, note Fig. 2, having ring plugs 25 at the upper ends thereof. In these passages are disposed pins 26, having heads 27 at their lower ends operating upon coil springs 28, the pins carrying outwardly of the plugs 25 catch devices 29, having bevelled surfaces 30.

Sufficient clearance will be provided in the ring plugs to facilitate slight radial movement of the catch devices 29 when the flange 15 is moved over the bevelled surfaces 30 in snapping the flange 15 of the tube 12 into engagement with these devices and, by rotating the tube 90°, the flat sides 16, note Fig. 4, can be moved into position to clear the catch devices in the operation of removing the syringe from the holder.

At 31 are shown spring fingers soldered, as seen at 32, to upper end portions 33 of a pair of spring tongs or body grippers 34 secured by screws 35 in vertically grooved portions in the enlarged diameter portion 18. The screws 35 have long collar portions 36, note Fig. 3, on which the tongs 34 are free to move as these tongs are manually operated against the action of the spring fingers 31 which tend to normally move the tongs away from each other.

At one side of the reduced portion 20 of the tubular body are a pair of apertured ears 37 in which a trigger catch 38 is pivotally mounted. The catch has a fingerpiece or operating end 39 which extends through an aperture 40 in the adjacent tong 34, this aperture being sufficiently long to also receive a trigger pin or catch device 41, as seen clearly in Fig. 3 of the drawing.

The pin 41 operates in an aperture 42 of the flange 19 and is adapted to seat under the lower portion 12' of the tube 12 or where this tube 40 joins the reduced end 43 thereof, with which the nozzle 13 is coupled. This pin holds the entire syringe in the raised position, as later described. The pin 41 has an annular groove 44, note Fig. 3, and the trigger catch 38 has a forked end 45 operating in the groove 44 to control movement of the pin 41 into inoperative position.

The catch has an offset shoulder 46 which is adapted to overlie the flange 19 and is held in this position by a spring 47 fixed to the fingerpiece end 39 of the catch 38 and operating upon the reduced portion 20 of the body.

From the foregoing description, it will be apparent that, after a syringe has been filled with the desired fluid to be injected into the body, the

syringe is placed in the device by simply snapping the flange 15 over the catch devices 29 so that the flanges are arranged beneath these devices, or lugs, as shown in Fig. 2. Then the syringe is pulled upwardly against the action of the springs 28 until the pin 41 automatically springs under the portion 12' of the tube 12. The spring 41 operates to move the trigger catch 38 and pin 41 in this operation.

The device is now ready for use and the operator grasps the tongs 34 and places the lower roughened ends 34' of the tongs on the flesh of the body and then moves the tongs toward each other against the action of the springs 31, so as to pinch or squeeze the flesh and raise a portion thereof, as diagrammatically seen at 43 in Fig. 1 between the ends 34' of the tongs, whereupon, a finger of the hand gripping and grasping the tongs can be utilized to actuate the trigger catch 38 to press the fingerpiece end 39 inwardly, thus withdrawing the pin 41 to release the syringe. The springs 28 will then suddenly advance the needle 14 of the syringe into the raised portion 48, as indicated in dot and dash lines in Fig. 1, whereupon, the plunger 17 can be moved downwardly to inject the fluid into the body.

Suitable shock absorbing means is preferably provided at the upper surface of the enlarged end 18 of the tubular body and in alignment with the flange 15 of the syringe, as illustrated by circumferentially spaced rubber bumpers 49 to prevent damage to the syringe in the rapid downward movement thereof.

In Fig. 5 of the drawing, I have shown merely the lower end portion of the tongs 34 of a device as shown in Fig. 1, but illustrating a modified lower end construction including inwardly projecting stop members, or lugs, 50 adapted to limit the upward movement of the pinched flesh. The stop members 50, thus provide means for accurately orienting or positioning the pinched flesh with respect to the retracted needle of the syringe, and for controlling the degree of penetration of the flesh in the downward movement of the syringe when released by actuation of the trigger 38. This element of control is particularly important in instances where, due to age or illness, the flesh may be soft or flabby.

Devices of the kind under consideration can be utilized in administering many types of injection into the body and are particularly desirable for use by individuals who periodically find the need for injecting insulin or the like into the body. It will be understood that, by reason of the pinching or squeezing action upon the flesh, a slight amount of feeling is attributed to this operation which, in turn, minimizes the feeling and eases the operation of piercing the needle 14 into the flesh.

An outstanding advantage of my device is that it enables a person to self-administer injections in areas of the body which were heretofore inaccessible without the assistance of another person. It will be noted that this advantage is directly attributable to my novel combination of a flesh pinching and positioning means with a trigger actuated syringe supporting and advancing mechanism. In this connection, it is to be understood that the particular manner of mounting the tong members on the device as shown in the drawing is merely illustrative of my invention and is not to be construed as limiting the same. Any pivotal or resilient supporting means may be employed which will provide a normally spaced relationship of the tong ends and will permit movement

of the tong ends toward each other in a common plane as the tongs are actuated to grasp or pinch a portion of flesh.

Having fully described my invention, what I claim as new and desire to secure by Letters Patent is:

1. A device for supporting and operating syringes, comprising an elongated tubular body, a syringe mounted in said body, the needle end portion of the syringe protruding from one end of the body and the plunger of the syringe being exposed at the other end thereof, a pair of spring tongs one end of which are fixed on the body at opposed sides of the upper end thereof and extending well below the lower end of said body, tensional means for normally urging the tongs in spaced relationship to each other, a pin movable radially of the lower end portion of the body and adapted to engage the syringe to support the same in raised position, tensional means engaging the syringe to support the syringe tensionally on said pin, and a manually operated member on said body and operatively engaging said pin, whereby actuation thereof will move the pin into inoperative position for releasing the syringe for sudden movement into operative position.

2. A device for supporting and operating syringes, comprising an elongated tubular body, a syringe mounted in said body, the needle end portion of the syringe protruding from one end of the body and the plunger of the syringe being exposed at the other end thereof, a pair of spring tongs one end of which are fixed on the body at opposed sides of the upper end thereof and extending well below the lower end of said body, tensional means for normally urging the tongs in spaced relationship to each other, a pin movable radially of the lower end portion of the body and adapted to engage the syringe to support the same in raised position, tensional means engaging the syringe to support the syringe tensionally on said pin, a manually operated member on said body and operatively engaging said pin, whereby actuation thereof will move the pin into inoperative position for releasing the syringe for sudden movement into operative position.

3. A device of the character described, comprising an elongated casing having a bore opening through opposite ends thereof, a syringe adapted for detachable mounting in the bore of the casing, the lower portion of the syringe having an annular seat, a pin mounted in the lower portion of the casing and adapted to extend into the bore to engage said seat to support the syringe in raised position, the upper portion of the syringe having, at opposed sides, projecting flanges, a pair of catch devices engaging said flanges, coil springs mounted in said casing for applying tension to said devices and the syringe when held in raised position by said pin, and a spring trigger pivotally mounted on said casing and operatively engaging the pin to move the same into inoperative position for suddenly releasing said syringe.

4. A device of the character described, comprising an elongated casing having a bore opening through opposite ends thereof, a syringe adapted for detachable mounting in the bore of the casing, the lower portion of the syringe having an annular seat, a pin mounted in the lower portion of the casing and adapted to extend into the bore to engage said seat to support the syringe in raised position, the upper portion of the syringe

having, at opposed sides, projecting flanges, a pair of catch devices engaging said flanges, coil springs mounted in said casing for applying tension to said devices and the syringe when held in raised position by said pin, a spring trigger pivotally mounted on said casing and operatively engaging the pin to move the same into inoperative position for suddenly releasing said syringe, and a pair of spring urged tongs fixed to opposite sides of the upper end of said casing, said tongs being adapted to support the body of a person in the operation of piercing the needle of the syringe into the body of the person.

5. The combination with a syringe of the character described, of a syringe supporting and operating device, said device comprising an elongated casing, a pair of spring urged tongs fixed at one end of the upper end of the casing, the other ends of the tongs extending beyond the lower end of the casing and directed toward each other to engage the body of a person, means on said casing for tensionally moving the syringe from a raised position to a lowered position, means on the casing engaging said syringe to support the same in raised position with respect to that part of the body engaged by said tongs, and manually actuated means on the casing for releasing said last named means to release the syringe for sudden movement in the direction of the body of a person for piercing the needle of the syringe into the body.

6. The combination with a syringe of the character described, of a syringe supporting and operating device, said device comprising an elongated casing, a pair of spring urged tongs fixed at one end of the upper end of the casing, the other ends of the tongs extending beyond the lower end of the casing and directed toward each other to engage the body of a person, means on said casing for tensionally moving the syringe from a raised position to a lowered position, means on the casing engaging said syringe to support the same in raised position with respect to that part of the body engaged by said tongs, manually actuated means on the casing for releasing said last named means to release the

5 syringe for sudden movement in the direction of the body of a person for piercing the needle of the syringe into the body, and shock absorbing means on the upper surface of the casing and registering with a flange portion on said syringe for yieldably checking rapid downward movement of the syringe by said tensional means.

10 7. The combination with a syringe of the character described, of a syringe supporting and operating device, said device comprising an elongated casing, a pair of spring urged tongs fixed at one end of the upper end of the casing, the other ends of the tongs extending beyond the lower end of the casing and directed toward each other to engage the body of a person, means on said casing for tensionally moving the syringe from a raised position to a lowered position, means on the casing engaging said syringe to support the same in raised position with respect to that part of the body engaged by said tongs, manually actuated means on the casing for releasing said last named means to release the syringe for sudden movement in the direction of the body of a person for piercing the needle of the syringe into the body, shock absorbing means on the upper surface of the casing and registering with a flange portion on said syringe for yieldably checking rapid downward movement of the syringe by said tensional means, 20 and inwardly projecting means on the second named end of the tongs providing a stop for limiting the degree of elevation of a portion of flesh and accurately positioning said elevated portion with respect to the needle of said syringe.

35 HENRY MALM.
